(57) **CLAIM**

The ornamental design for a belt attachment, as shown and described.

DESCRIPTION

FIG. 1 is a front and left side perspective view of our design for a belt attachment;

FIG. 2 is a rear, bottom and right side perspective view thereof;

FIG. 3 is a front view thereof;

FIG. 4 is a rear view thereof; and,

FIG. 5 is a right side view thereof, with the left side view being a mirror image thereof.

The broken line showing of elements is included for the purpose of illustrating environmental matter and forms no part of the claimed design.
